UNITED STATES PATENT OFFICE

LEO W. KENNEDY, OF DETROIT, MICHIGAN

DESIGN FOR A CANDY CASE

Application filed July 28, 1930. Serial No. 36,497. Term of patent 14 years.

To all whom it may concern:

Be it known that I, LEO W. KENNEDY, a citizen of the United States of America, residing at Detroit, in the county of Wayne and State of Michigan, have invented a certain new, original, and ornamental Design for Candy Case, of which the following is a specification, reference being had therein to the accompanying drawings, forming a part thereof, in which,

I claim:

The ornamental design for a candy case substantially as shown.

LEO W. KENNEDY.
